(57) **CLAIM**

The ornamental design for a vehicle bonnet, as shown and described.

DESCRIPTION

FIG. 1 is a left front perspective view of a vehicle bonnet according to the present invention.

FIG. 2 is a right rear perspective view of the vehicle bonnet shown in FIG. 1.

FIG. 3 is a right front perspective view thereof.

FIG. 4 is a left rear perspective view thereof.

FIG. 5 is a front view thereof, slightly elevated.

FIG. 6 is a rear top view thereof, slightly lowered.

FIG. 7 is a left side view thereof.

FIG. 8 is a right side view thereof.

FIG. 9 is a top view thereof; and,

FIG. 10 is a left front view of the vehicle bonnet shown in FIGS. 1-10, with the bonnet mounted on a vehicle, and the rest of the vehicle shown in de-emphasized and half-tone portions so as to illustrate environmental structure. These portions form no part of the claimed invention. More particularly, in FIG. 10, the inventive bonnet is shown within the broken line, and any elements shown outside of the broken line form no part of the claimed invention, but are instead included to show environmental aspects thereof.
